UNITED STATES PATENT OFFICE.

GEORGE E. C. SCHMIEDEL, OF BROOKLYN, NEW YORK.

DESIGN FOR WOVEN FABRIC.

No. 38,198.

Specification for Design.

Patented Aug. 28, 1906.

Application filed May 21, 1906. Serial No. 318,087. Term of patent 3½ years.

To all whom it may concern:

Be it known that I, GEORGE E. C. SCHMIEDEL, a citizen of the United States, residing at Brooklyn, in the county of Kings and State of New York, have invented a new, original, and ornamental Design for Woven Fabrics, of which the following is a specification, reference being had to the accompanying drawing, forming part thereof.

The figure is an elevation showing the design of the fabric.

I claim—

The ornamental design for a woven fabric, as shown.

GEORGE E. C. SCHMIEDEL.

Witnesses:

FRANK WILKINSON,
HENRY HERRING.
